UNITED STATES PATENT OFFICE

2,637,379

GUN TYPE OIL BURNER WITH COMBUSTION HEAD STRUCTURE

James M. Carroll, Philadelphia, and Thomas W. Murphy, Narberth, Pa., assignors to The Monarch Manufacturing Works, Inc., Philadelphia, Pa., a corporation of Delaware

Application August 27, 1949, Serial No. 112,724

14 Claims. (Cl. 158—76)

1

This invention has general reference to fluent fuel burners and, more particularly relates to an improved combustion head conveniently, although not essentially, well adapted for installation in oil burning domestic heating plants, but which may also be incorporated to advantage in connection with larger fluent fuel burners.

More specifically the instant invention has for its primary object improvements in fluent fuel burners, of the type disclosed in pending applications for patent, respectively, filed by Thomas W. Murphy (one of the instant applicants) under Serial No. 694,752, dated September 4, 1946; and James M. Carroll (the other of the instant applicants) under Serial No. 792,282, dated December 17, 1947, now U. S. Patents 2,505,337 and 2,531,027, respectively.

Another object is to provide a burner of the type above referred to whereby a much better and more intimate mixing of the fluent fuel and combustion supporting air is positively assured; the shape of the flame or fire is rendered adjustable as desired or expedient; and escape of any of the combustion supporting air is to all practical intent eliminated with an attendant increase in the flame efficiency.

Other objects and advantages of our invention will hereinafter appear or be specifically noted, while said invention briefly consists in certain features of construction, and the novel combinations of parts described and typically illustrated by the accompanying sheets of drawings; wherein:

Fig. 1 is a broken longitudinal section through a conventional type domestic oil burner embodying our present improvements.

Fig. 2 is a front end view of the burner taken as indicated within the confines of the arrows II—II in Fig. 1.

Fig. 3 is a cross-section through the burner taken on the plane designated III—III in Figs. 1 and 4.

Fig. 4 is a relatively larger scale longitudinal section taken approximately as indicated by the plane indicating arrows IV—IV in Fig. 2.

Fig. 5 is a similar section to the preceding figure on a corresponding scale, but taken on the plane designated V—V in Figs. 2 and 4.

Fig. 6 is an exploded perspective view of the air turbulator, with associated choke and stop rings, later on herein fully described.

Fig. 7 is a perspective view of a secondary air flow defining component, hereinafter fully described.

Fig. 8 is a perspective view of an air director, incorporated with the component of Fig. 7.

2

Fig. 9 is an air guide also incorporated in the controlling component of Fig. 7; and,

Fig. 10 is a perspective view of a spider device serviceable to mount and hold the combustion head of this invention in assembly.

In describing the embodiment of our invention exemplified by the three sheets of illustrations herewith specific terms will be employed for the sake of clarity, but it is to be understood the scope of said invention is not thereby limited; each such term being intended to embrace all equivalents which perform the same function for an analogous purpose.

Referring more in detail to the drawings a typical oil burner housing is comprehensively designated 11, said housing including an off-set section 12 for the blower fan 13, as well as a blast or air tube 14 having a stop ring 15 at its free or open end, that is rigidly secured in place by aid of screw-studs 16, Fig. 5. The stop ring 15 is provided with a shallow exterior groove 17, Figs. 1, 3 and 4 for a purpose later on herein again referred to; whereas 18 indicates a conventional closure plate for the burner housing remote from said stop ring 15.

The burner combustion head comprehensively marked 19, of our present invention comprises an improved type of cylindrical air-turbulator 20, see Fig. 6 to best advantage, preferably made of a desirable length of stainless steel tubing to embody a forward plain end 20' for inset reception of a concave-convex air choke ring section 21, and a rear end with an inwardly angled flange 22 embodying diametrically opposed pairs of spaced projections 23 useful to correctly position the turbulator 20 to hold same against any turning movement, as later on fully explained. In addition it is to be noted the main wall of the air turbulator 20 is lengthwise slotted at regular intervals to provide mainly inwardly directed blades 24 of curvilinear cross-section that serve to direct the main body of the combustion supporting air annularly about the oil jet nozzle 25 with a continuous swirling motion. The jet nozzle 25 is suitably secured to the adjoining end of the fuel supply line 26, with capacity for axial adjustment as hereinafter set forth.

Attention is now directed to the fact that the angled flange 22 of the turbulator 20 is fitted with a closure element, which we preferably term, a closure plate 27 as seen in Figs. 1, 4, 5 and 7. This plate 27 is provided with a surrounding lip 28 adapted to snugly engage about the turbulator angled flange 22; while said plate includes a central orifice 29, with a concentric annular series

of helically pitched vanes 30 effective to direct secondary air centrally through said plate 27. Incidentally, while the pitched vanes 30 are shown in the drawings as projecting beyond both planar faces of the plate 27, it is to be expressly understood they may be directed from one side only, preferably forward or toward the tip 31 of the nozzle 25.

Referring again to the closure plate 27 it will be further remarked, on reference to Fig. 7 more particularly, that it is provided with diametrically spaced holes 32, 33 and 34, the respective purposes whereof will now be explained in conjunction with the assembling of the burner combustion head 19 and the associated mounting or spider device 35, Fig. 10. In the first place the plate 27 is equipped with a forwardly-directed and concentrically-related tubular air-flow director 36, Fig. 8, having a rear end flange 37 with diametrically spaced holes 38, whereby said controller is rigidly attached to the plate 27 as by rivets 39 for example, see Figs. 2 and 4, which also are engaged through the plate holes 34 above referred to. It is also to be noted that the bore of the controller 36 is of a diameter to surround the forward portions of the pitched vanes 30, as clearly shown in Figs. 4 and 5; while the central orifice 29 of the spiraling plate 27 is fitted with a co-axial air-guiding sleeve 40, Figs. 4, 5 and 9, of an inner diameter to slidably engage the jet nozzle 25. The sleeve 40 has its forward end tapered at 41 for a purpose later on herein set forth; whereas the rear end thereof embodies a reduced extension 42, for snug engagement through the central orifice 29 of the plate 27, with length sufficient to have its free end peened over, or expanded at 43, into abutment with the rear confronting face of said plate 27, as readily seen on an examination of Figs. 4 and 5. It will thus be apparent that the parts 27, 36 and 40 are attached in assembly; whereupon said assembly is rigidly coupled to the turbulator 20, and to the mounting or spider device 35 by aid of tubular spacers 44 and bolts 45. At this juncture it is to be particularly noted that the tubular spacers 44 have their bores 46 in part screw-threaded at 47, and that the bolts 45 are correspondingly screw-threaded at 48 for coaction with the bore threadings 47; also that the shank portions of said bolts adjoining their heads 49 are not only engaged through the holes 33 in the plate 27 but that they also seat in the respective slots defined by the spaced projections 23, of the turbulator angled flange 22, see Fig. 4. Thus it will be readily seen that by applying a suitable tool to the cross groove 50 in the bolt heads 49, for instance, the assembled parts 20, 27, 36 and 40 are firmly clamped to the spacers 44 with the threaded ends 48 of the bolts 45 projecting outwardly, in position for free passage through the apertures 51 proximate the ends of the spider diametric arms 52, see Fig. 4; whereupon appropriate lock washers 53 and nuts 54 are applied, in an obvious manner.

The mounting or spider device 35 embodies a central orificed boss 55 the bore of which is adjustable along the fuel supply pipe 26 and is adapted for rigid fixture thereto, in the desirable position, by aid of a screw-stud 56, as readily understood by those conversant with the art. In addition the spider device 35 embodies another pair of radial arms 57, Figs. 3, 5 and 10, including tubular end portions 58 for support of a pair of parallel electrode holders 59.

Each electrode holder 59 is preferably of 75

porcelain and of known type, but it is to be particularly observed that the forward ends 60 thereof are projected but slightly beyond the turbulator closure plate 27 with snug engagement through the associated hole 32, as clearly shown in Fig. 5. Furthermore each electrode holder 59 is secured in position by aid of a clamp screw 61 engaged in the respective spider tubular portion 58. Positioning of the forward ends 60 of the electrode holders 59, as just above set forth, serves to prevent obstructive interference with the desired air circulation in the turbulator 20. Another advantage inhering to the retraction of the electrode holders 59, to the position shown and described, enables the provision of certain tubular surface areas 62 that serve for protection, against carbonization, of the electrode wires 63, due to heat and fuel oil traveling back along said wires, with resultant damage to said wires and their connector means 64, whereas the groove 17 hereinbefore mentioned serves as a drain outlet for any fuel oil that may collect in the blast or air tube 14 as readily understood by those conversant with the art.

Incidentally the forward end of the fuel supply pipe 26 is threaded at 65, and the jet nozzle 25 is provided with diametrically opposed flats 66, for example only, in order that said nozzle may be axially adjusted, as desired or expedient, relative to the spark terminals 67 of the electrode wires 63, Figs. 2, 4 and 5.

Referring back again to the turbulator 20, and in order to make provision for changing the shape of the flame or fire, said turbulator is provided with a movable flat strip or static band 68, preferably of stainless steel, having the ends 69 retroverted or opposingly curved over for reception of a pronged spring grip 70 having its prongs engaged in the said retroverted ends 69 and normally effective to hold the band 68 firmly around the turbulator 20 in the desired position. On the other hand it will be readily apparent that, when the band 68 is moved to either end in Fig. 1, or lengthwise of the turbulator 20 the grip 70 will automatically function to again secure said band in its changed position. It will now be self-evident that, having all of the parts assembled as before described, the combustion-head 19 is ready for application of the choke-ring 21 and the split ring 72, preferably of rectangular section, to the forward end of the combustion-head 19, in an obvious manner, with frontal engagement in the counter-bore 73 of the stop ring 15. Note should be had at this juncture that the split ring 72 is of a size to mask the tips of the tangentially-inclined vanes 30 for a purpose later on herein set forth.

Having described the structural features of our invention its manner of operation will be self-evident to those conversant with the art, but it is desired to emphasize herein certain functional aspects that render the combustion-head highly efficient in use. In the first place by our instant improvements we have substantially cleared the air turbulator 20 of the interior obstructions that previously interfered with the continuous swirling motion of the main body of the combustion supporting air about the fuel jet nozzle 25, and by provision of the turned rear angle-flange 22 with which the lipped edge portion 28 of the closure plate 27 snugly engages and the use of the split ring 72, escapement of air from off the forward end edges of the blades 24 is effectively prevented, whereby all combustion supporting air must pass through said blades 24,

or through the central secondary air helically-pitched vanes 30 immediately around the nozzle 25 and from thence into the mixing zone beyond the forward end of the tubular air-flow controller 36. It is also to be noted that the secondary air-flow director 36 and air guiding sleeve 40 are concentric in respect to the turbulator 20 with a resultant direct flow through the swirling air in said turbulator. Incidental to providing the guide sleeve 40 with the forward taper end 41 it will be also apparent that a portion of the approximately cylindrical flow of the secondary air will be directed into and across the fuel spray emitted from the nozzle tip 31, as well as across the terminal portions 67 of the electrode wires 63; and adjunctively it is to be remarked that the major portions of said wires 63 outwardly of the holders 59 are continuously subjected to the action of the swirling air in the turbulator 20. As a result it will be obvious that the electrode wires 63 are kept substantially free from carbonization or other accumulative matter much longer than heretofore possible.

Finally, while we have shown and described our improved fluent fuel burner combustion head in the best form at present known to us, it is to be understood that various changes may be made in the form and arrangement of the constituent parts of the same without departing from the spirit of the following claims.

Having thus described our invention, we claim:

1. A fuel burner comprising a blast tube, fuel supply means, a fuel burning nozzle in said blast tube, means for supplying combustion supporting air thereto, an air turbulator in the form of a tube disposed longitudinally within said blast tube carrying a plurality of circumferentially spaced longitudinally disposed blades constructed to direct the air inwardly with continuous swirling motion, a closure in the form of a plate attached across one end of said turbulator tube, a plurality of angled vanes annularly arranged in openings on said closure plate to whirl the air passing therethrough, an air director tube contiguously surrounding the outer edges of said angled vanes and extending forwardly of said closure plate into said turbulator tube, said air director tube being substantially coaxial with said turbulator tube, and an air guide sleeve disposed coaxially within said air director tube, said air guide sleeve having an air guiding surface in contact near its outer end with the inner edges of said angled vanes and extending into said turbulator tube, whereby the air director tube and air guide sleeve coact to define a substantially axially directed annular passage disposed forwardly of said angled vanes in said turbulator tube for passage of air whirled by said angled vanes.

2. The invention as defined in claim 1, wherein the air guide sleeve has an inwardly tapered forward end providing an air guide surface extending toward the axis of the air guide sleeve.

3. In a fuel burner, a blast tube, means for driving combustion supporting air through said blast tube, a fuel feed nozzle in said blast tube, a fuel feed conduit connected to said fuel feed nozzle, an air turbulator tube mounted substantially coaxially within said blast tube, a plurality of blades disposed substantially longitudinally on said turbulator tube with spaces therebetween, said blades being constructed to direct air inwardly through said spaces with continuous swirling motion in said blast tube, and a movable band encircling the turbulator blades and slid-

ably adjustable longitudinally of said turbulator blades, the width of said movable band being less than the length of the spaces between said turbulator blades whereby the distribution of air flow through the turbulator blades may be varied independently of the air flow rate therethrough, for variation of the shape of the burner flame, by adjusting said band longitudinally along said turbulator blades.

4. The invention as defined in claim 3 further characterized by the fact that the movable band has a pair of spaced adjacent free ends, and by the provision of spring means constructed and arranged for attachment to said free ends, said spring means being effective when so attached to urge the free ends of the band toward one another to establish frictional contact of the band with said blades.

5. In a fuel burner, a blast tube, means for driving combustion supporting air through said blast tube, a fuel feed nozzle in said blast tube, a fuel feed conduit connected to said fuel feed nozzle, air whirling means including a plate transversely mounted on said fuel feed conduit within said blast tube, said plate having angled vane means for whirling said combustion supporting air in said blast tube, a rigid support non-rotatably mounted in said blast tube rearwardly of said transverse plate, an electrode holder in the form of a sleeve of non-conducting material supported by and extending between said support and said transverse plate lengthwise of said blast tube, an electrode mounted in said sleeve, and electric connecting means through which said electrode may be energized to induce fuel combustion at said nozzle, said electrode holder sleeve having a stepped inner bore including a relatively narrow-bore portion gripping the electrode at the rear end only of the sleeve, and a relatively wide-bore portion at the forward end of the sleeve, there being free space between the electrode and said wide-bore portion, whereby said wide-bore portion affords a substantial area of non-conducting material surrounding the electrode.

6. A combustion head for a fuel burner of the type described comprising in combination, a tubular air turbulator having front and rear ends, the rear end having an inwardly directed flange, said turbulator having a plurality of circumferentially spaced longitudinally disposed blades constructed to direct the air inwardly with continuous swirling motion, a choke ring in the front end of said turbulator, said choke ring being constructed to direct said air inwardly, a closure for the rear end of the turbulator carrying an annular series of helically-pitched vanes arranged about a central orifice, said closure having openings between said helically-pitched vanes through which air may pass, a secondary air flow director tube attached to said closure in contiguous surrounding relation to said vanes and extending forwardly into said turbulator, a concentrically related air guiding sleeve secured at its rear end in the turbulator closure central orifice, means securing the parts aforesaid in rigid assembly, a spider device for mounting the turbulator assembly on the burner fuel nozzle and supply line, tubular spacers extending between the turbulator closure and aligned arms of the spider device, tubular electrode holders engaged through other aligned arms of the spider device with slight projection into the turbulator, and means whereby the turbulator assembly, said spacers, said elec-

7
trode holders and the spider device are rigidly connected together.

7. The invention of claim 6 wherein the turbulator rear end flange embodies diametrically opposed pairs of spaced projections; wherein the means securing the turbulator assembly, tubular spacers, electrode holders and the spider device rigidly together consist of bolts passed through the turbulator rear end closure, tubular spacers and spider device; and wherein the bolt shank portions, adjoining the heads thereof, seat in the slots between the spaced projections of each pair aforesaid to prevent relative turning between the turbulator and the spider device.

8. The invention of claim 7 further characterized by the tubular spacers having a portion of their respective bores screw threaded, and wherein the through bolts are correspondingly threaded for engagement with the spacer bore threadings to rigidly attach the spacers to the turbulator assembly.

9. The invention of claim 6 wherein a split ring is associated with the choke ring and abuts the forward ends of the turbulator blades, and wherein the split ring in the choke ring is of rectangular cross section, and wherein the radial dimension of said split ring equals the radius of the tip ends of the tangentially pitched blades whereby escape of any of the combustion supporting air thereat is effectively prevented.

10. The invention of claim 6 wherein the closure for the turbulator rear end is in the form of a plate; and wherein said vanes project beyond both planar faces of the closure plate.

11. The invention of claim 10 wherein said plate embodies a surrounding lip to snugly engage around the turbulator rear end inwardly directed flange.

5 12. The invention of claim 6 wherein the secondary air flow controller tube carries a surrounding flange at one end which is attached by appropriate means to the forward face of the turbulator closure so as to closely surround the pitched vanes.

10 13. The invention of claim 6 wherein the air guiding sleeve is tapered at its forward end; and wherein the rear end embodies a reduced extension for passage through the turbulator closure central orifice; and wherein said reduced extension provides rigid attaching means for the sleeve to the closure.

15 14. The invention of claim 6 wherein the electrode holders are porcelain and wherein each said holder affords a surrounding surface area about and in spaced relation to the associated electrode wire effective to protect the latter against carbonization.

JAMES M. CARROLL.
